SAFETY RAZOR

Peter Nicholas Peters, New York, N. Y.

Application June 3, 1941, Serial No. 396,371

6 Claims. (Cl. 30—77)

The present invention relates to safety razors and, more particularly, to the guard members forming a part thereof.

It is well known that, in shaving, a certain amount of pressure must be applied to the razor so as to enable the blade edge to maintain a close, continuous contact with the skin. When shaving pressure is insufficient, hair shafts merely bend down, duck under the advancing blade edge, and slip through intact. To make it easier for the average man to apply correct shaving pressure, safety razors are usually designed to provide what is known as a "positive" blade edge exposure, defined as the distance by which the cutting edge projects beyond the line tangent to both, the cap and the guard.

Unfortunately, because the human face has an irregular surface, any fixed blade exposure, however carefully determined, is bound to be a compromise. Thus, if designed correctly for shaving the comparatively flat surface of the cheek, it is apt to be insufficient for the concave underside of the jaw and altogether excessive for the convex chin, where most shaving casualties take place.

Attempts have been made in the past to vary the blade exposure by means of a flexible spring guard. None of these attempts was successful because, in acquiring flexibility, the new guards were deprived of their primary and most important function, namely, that of effectively stretching the skin ahead of the cutting edge. If a flexible spring guard was flexible enough to provide a variable blade edge exposure at normal shaving pressures, it was no longer rigid enough to stretch the skin in front of the cutting edge. Conversely, if it was rigid enough to accomplish such stretching, then it was not sufficiently flexible to vary the edge exposure, unless subjected to excessive and, therefore, dangerous pressures.

Another drawback of earlier flexible guards was attributable to their rigidity lengthwise. The degree of deflection of the entire guard was usually determined by the highest spot which it was contacting at the time. This action often bared the blade corners at inopportune moments and permitted them to inflict painful cuts.

The main object of the present invention is to provide a guard member affording a blade edge exposure which can readily vary at normal shaving pressures without at the same time losing any of its own efficiency as a skin stretching mechanism. Another object is to provide such a guard capable of yielding not only perpendicu-

larly to the surface of the skin, but also parallel to it; in other words, a guard which is compressible as well as flexible. Still another object is to provide a guard member the action of which on the skin is entirely disassociated from and independent of the blade clamping means. Earlier guard members, made of some deformable material throughout, did not fulfil this important requirement, with the result that their inevitable deformation in clamping the blade was frequently transmitted to the skin contacting portion, distorting the latter and throwing it out of alignment with the blade edge.

It is also an object of this invention to provide a razor having the above enumerated advantages and in which, at the same time, proper use is made of heat conducting and insulating materials to insure a correct shaving technique, as is fully described and explained in my U. S. Patent No. 1,821,574, and further elucidated in my copending application, Ser. No. 279,005 now Patent No. 2,298,508.

Other purposes, not specifically mentioned above, will appear from the specification which follows and from the accompanying drawing, in which:

Figures 1 and 2 are diagrammatic views illustrating the principle involved in the present invention. Figure 3 is a perspective view of an unassembled three piece safety razor of the familiar double edge type, but equipped with a guard member in accordance with the present invention. Figure 4 is a cross section taken along the line 4—4 of Figure 5. Figure 5 is a perspective view of a guard member embodying the present invention, with a portion broken off. Figure 6 is a detail showing a variant of the guard member in cross section similar to that shown in Figure 4, but without the cap or handle.

Referring to the figures in detail, 1 is the handle of a standard safety razor, 2 is the guard member embodying the present invention, 3 the blade, 4 the cap, 5 the central threaded pin on the cap which connects the cap to the handle 1 in the assembled device. In addition to the pin 5, there are shown the two positioning pins 6, 6. Holes 7 in the guard member 2, and holes 8 in the blade allow the passage of the pins 5 and 6 through the guard member and blade. The threaded pin 5 is threaded into the threaded hole 9 of the handle 1 when the device is assembled. The guard member 2 is provided with grooves 10 into which is fitted the guard 11, made of a resilient, flexible and compressible

material, such as rubber, either natural or synthetic (e. g. neoprene or its equivalents). It will be noted that the guard member 2 is composed of two elements, the blade contacting portion 12, shown here as made of brass, although it may be made of any other rigid, unyielding material, such as die cast zinc alloys, plastics, glass and even cement, and the skin contacting portion, viz., the guard 11, made of an elastic material. The body portion 12 is made preferably of metal because of its ability to store and conduct heat. The guard 11, if made of rubber, is a non-conductor of heat. While the guard 11 is shown as anchored in the grooves of the guard member, obviously, it may be fitted onto it in various other ways, not shown here because such ways are too well known in the art to require illustration. The guard 11 may be further secured in the guard member by cement, or, after being snap-fitted into the grooves, retained there under stress, either tensional or compressional, or both, as is illustrated in Figure 6, wherein two different modes of fitting are shown, one on each side of the guard member.

It is important to observe that, whatever the modification of the invention as here shown may be adopted, in all cases the action of the skin-contacting and exposure regulating guard 11 is wholly independent of the action of the blade contacting portion 12.

In the illustration, Figure 6, the elastic guard 11 is made of a single piece of neoprene, with a central cut-out substantially conforming to, but slightly smaller than the cross section of the main body of the guard member, as defined by the grooves 10. During the assembly, the gasket-like neoprene guard is stretched, slipped over the rigid portion of the guard member and allowed to snap into the grooves, which may, or may not, have a cement coating to further secure permanent bond between the main body portion of the guard member and the guard 11.

There is a distinct advantage in having the elastic guard completely encircle the rigid portion of the guard member and overlap the cap corners. Such a construction not only protects the razor when it is accidentally dropped on the floor, but it also enables the user to grasp the razor head without having his fingers come in contact with the main guard body previously scalded in hot water, or with the jagged non-sharpened ends of the blade.

The diagrammatic illustrations, Figures 1 and 2, are intended to clarify the underlying principle on which the present invention is based. In Figure 1, 13 is the guard of a standard safety razor, shown only fractionally, 14 is the cap, 15 the blade, and *d* the distance which the blade edge projects beyond the tangent common to the guard and the cap, designated above as the "positive" exposure of the blade edge. In Figure 2, a guard such as is embodied in the present invention is illustrated. When the razor is pressed

downward, the point 0 is deflected at 0'. When it is moved forward during the shaving operation, the point 0' assumes the position at 0''. The positions of the guard 11 when so deflected are indicated in dot and dot-dash lines respectively. It is clear that the combined pressure of the razor downward and its thrust forward form a resultant force acting substantially in a direction perpendicular to the edge of the guard, 10 i. e., the point 0 of the guard 11 is compressed from the point 0 to the point 0'' in this operation. Having provided a guard capable of compression, I have, therefore, provided means for properly regulating the edge exposure under normal shaving pressures.

While only a double edged razor has been illustrated in the drawing, obviously, the invention is equally applicable to single edged razors. The present invention is an improvement on my Patent No. 1,821,574, and, for best results, should be practiced in accordance with the shaving technique set forth in my copending application Ser. No. 279,005 now Patent No. 2,298,508, issued Oct. 13, 1942.

I claim:

1. In a safety razor, a guard member comprising a rigid, unyielding blade contacting portion and a resilient and compressible member extending sufficiently far out of said rigid portion to be flexible for regulating the blade edge exposure.

2. In a safety razor, a guard member, comprising a blade contacting portion of rigid, unyielding, heat-conducting material, and a member of resilient, compressible and heat insulating material for extending sufficiently far out of said rigid portion to be flexible for regulating the blade edge exposure.

3. In a safety razor, a guard member comprising a blade contacting portion of rigid, unyielding, heat-conducting material, and a member of resilient, compressible and heat insulating material extending sufficiently far out of said rigid portion to be flexible for regulating the blade edge exposure, said resilient member being capable of yielding only at or near the points at which external pressure is applied.

4. In a safety razor, a guard member comprising a rigid unyielding blade contacting portion, and an elastic skin contacting member embracing said rigid portion.

5. In a safety razor, a guard member comprising a rigid, unyielding blade contacting portion, a resilient and compressible skin contacting member extending sufficiently far out of said rigid portion to be flexible, and means on said rigid portion for attaching said flexible member thereto.

6. In a safety razor, a guard member comprising a rigid, unyielding blade contacting portion provided with a groove formation and an elastic member snap-fitted into said groove formation and held therein under stress.

PETER NICHOLAS PETERS.
